AMMUNITION

William J. Lowes, Chicago, Ill., assignor to Harris
Trust and Savings Bank, Chicago, Ill., a cor-
poration of Illinois, as trustee

Application June 25, 1943, Serial No. 492,257

6 Claims. (Cl. 102—64)

1

My invention relates in general to ammunition, but more specifically to a grenade or shell which may be thrown by hand, or which may be projected by a propelling charge from a mortar or from a rifle grenade launcher.

The shell unit comprises in general a grenade body filled with explosive and having fin structure at one end and at its other end having a nose assembly within which are elements controlled upon impact of the shell with the terrain to effect ignition of a fuse for explosion and disruption of the grenade body.

An important object of my invention is to provide, in the fuse controlling assembly, a movable explosive impact member or nose provided with a primer or firing cap engageable, upon impact of said impact element with the terrain, with a firing pin for explosion, and ignition of the fuse for explosion of the grenade body.

A further object is to provide improved safety means normally held interposed between the priming cap and the firing pin by latch mechanism from which the safety means may be manually released when the shell is to be thrown by hand, and which latch means will automatically release the safety means when the shell is projected from the mortar or other weapon by a propelling charge.

Still another object is to provide latching means, which, upon projection of the shell by a propelling charge, will be controlled by inertia for release movement of the safety means so that, upon impact of the impact member with the terrain, the firing cap may engage the firing pin for the explosion to set off the fuse, and with such explosion of the impact member tending to hurl the shell back into the air for explosion of the shell body while in the air by the fuse which has been accordingly timed.

Still another object is to provide the fin structure with a bore for receiving the end of a rifle, or a rifle attachment, for rifle projection of the shell, or to receive a cartridge holder and cartridge when the shell is to be projected from a weapon such as a mortar.

The above referred to and other features of my invention are shown embodied in the structure shown on the accompanying drawings in which:

Figure 1 is a side elevation of the shell;

Figure 2 is a section of plane II—II of Figure 1 of the shell body and fin structure showing the application of a blank cartridge and a supporting bushing therefor in the bore of the fin structure for mortar firing of the shell;

2

Figure 3 is a section of the cartridge supporting bushing before insertion into the fin structure bore;

Figure 4 is a section like Figure 2 but showing the fin structure bore receiving a rifle attachment for projection of the shell from a rifle;

Figure 5 is an end view of the fin structure;

Figure 6 is an enlarged section on plane II—II of Figure 1 of a portion of the shell body and the impact structure frame showing the retention pin and the safety pin or bar in normal position;

Figure 7 is a section on plane VII—VII of Figure 6;

Figure 8 is a section on plane VIII—VIII of Figure 7;

Figure 9 is a section like Figure 7 but with the retention pin withdrawn and the safety bar released from the safety latch structure; and

Figure 10 is a section like Figure 6 showing the arrangement of the various parts upon impact of the impact member firing cap with the firing pin.

The shell comprises the substantially elliptical body 10 filled with a suitable explosive and 25 serrated on its outsides to provide segments 11. Intermediate its ends the body has the cylindrical belt 12 which will act as a piston when the shell is to be fired from a weapon such as a mortar. The inner end wall of the body 10 has the opening

30 13 in which is secured the end 14 of the body 15 of the fin structure F, fins 16 extending from the body in radial direction and with the radial extent of the fins such that their outer edges may engage in the bore of a mortar to assist the piston belt 12 of the body 10 in guiding the shell through the mortar bore, the fins also serving to guide the flight of the shell.

Mounted on the outer end of the grenade body 10, concentric therewith, is a nose frame 17 having the outer dome-shaped or substantially semi-spherical end 18. This frame has the exteriorly threaded flange 19 extending from its base for threaded engagement in the outer end of the grenade body 10 to seat against the annular

45 shoulder 20. The domed end 18 has the cylindrical passageway 21 therethrough concentric with the frame 17 and the body 10, and axially movable in this passageway is the impact member or nose 22 in the form of a cylindrical cartridge

50 having the head 23 at its inner end and intermediate its ends a circumferential ridge 24 which normally engages against the inner side of the domed end 18, as shown on Figure 6. The cartridge is filled with suitable explosive material and in its head it has the firing cap 25.

The base 26 of the nose frame 17 has a threaded opening therethrough for receiving the plug 27 from which a post 28 extends axially in the frame 17 and terminates in a firing point or pin 29 in alignment with the firing cap 25. The base 26 and the plug 27 form a closure for the outer end of the grenade body 10, the plug having the hole 30 therethrough for a fuse 31, the interior of the nose frame 17 constituting a firing chamber 32 for the fuse. When, after projecting of the shell, the impact nose 22 impacts the terrain or an obstruction and is shifted inwardly to explode upon engagement of its firing cap with the firing pin 29, the ignited fuse will, after a predetermined time interval, ignite the explosive charge in the grenade body 10.

Safety means for normally preventing engagement of the impact nose firing cap with the firing pin comprises a safety pin 33 and a retention pin 34. The safety pin is shown in the form of a bar insertable through the opening 35 in the side of the nose frame 17 to extend normally diametrically through the firing chamber 32 with its inner end resting on a ledge 36 at the opposite side of the frame 17, the bar being thus normally disposed between the firing cap and the firing pin, and the bar inwardly of its middle point having upwardly extending cross ridges 37 engaging the head 23 of the impact nose to hold it with its ridge 24 normally in engagement with the inner side of the domed end 18 of the frame 17, as shown on Figure 6.

The retention pin 34 is shown in the form of a flat bar insertable through a passage 38 in the side wall of the frame 17 for extension radially in the firing chamber 32 with its inner end between the safety bar 33 and the firing pin, as shown in Figures 6 and 7. A ring 39 at the outer end of the retention pin facilitates withdrawal thereof at the proper time before the shell is to be thrown. Thus the safety pin and the retention pin are normally interposed between the firing pin and the impact member firing cap.

At its outer end the safety pin 33 has a head 43 normally fitting into a recess 41 in the frame 17 to shut off the firing chamber 32 from the exterior, a grip flange or knob 42 being formed at the outer end of the pin so that it may be grasped for manual pulling when the shell is to be thrown by hand.

A compression spring 43 extending between the side wall of frame 17 and the safety pin 33 tends to swing the safety pin out of its normal position (counterclockwise Figure 7), such swing being normally resisted by latch mechanism. This latch mechanism comprises a latch bolt 44 shiftable in a bore 45 in the base wall 26 of the frame 17, the bore at its inner end being closed by a plug 46. The latch bolt terminates in a head 47 between which and the base 26 is interposed a spring 48 which tends to hold the bolt out. The latch bolt head has the latch pin 49 extending therefrom for engagement normally in the inner end of a longitudinally extending slot 50 in the end of the safety pin, from the outer end of which slot a transverse slot 51 extends to the rear edge of the safety pin, as shown on Figures 7 and 9. When the safety pin is thus held in its normal position against swing by the spring 43, the spring 48 will urge the latch bolt upwardly against the inner end of the safety pin to hold the safety pin ridges 37 against the impact nose to hold this nose in its normal position, as shown in Figure 6.

If the shell is to be thrown by hand, the safety pin 33 will first be released from the latch bolt

44, this being accomplished by a short outward pull of the safety pin to bring the outer end of the longitudinal slot 50 into register with the latch pin 49 so that the spring 43 may swing the safety pin with its inner end away from the ledge 36 and with the central portion of the safety pin away from its normal position between the impact member firing cap and the firing pin, as shown on Figure 9, the pin coming to rest 10 when its inner end strikes the wall of the frame 17 at the end of the recess 52 in the wall. After release of the safety pin, the retention pin will still be in with its inner end between the firing cap and the firing pin, and just before the shell is thrown, the retention pin is pulled out. Now, when the projected impact nose hits the terrain or other obstruction, it will be shifted inwardly in the frame 17 for engagement of its firing cap with the firing pin, as shown in Figure 10. The 20 impact nose or cartridge will then explode and create fire in the firing chamber 32 for ignition of the fuse 31 and then ignition of the explosive charge within the grenade body 10. When the impact nose or cartridge is fired upon hitting the ground, the explosion thereof will tend to recoil and throw the shell back up into the air, and the rate of burning or timing of the fuse 31 is such that the explosive within the grenade body 10 will be ignited when the shell is in the air 30 after such recoil or rebound, thus making the shell much more effective in destructiveness.

Provision is made for projecting the shell from a weapon such as a mortar by a propelling charge as from a cartridge. For this purpose, the body 15 of the fin structure F is provided with a cylindrical axial bore 53 into which a bushing 54 may be inserted for seating a blank cartridge 55. Spring legs 56 on the bushing will tend to hold it frictionally in the bore 53, the cartridge 40 being inserted through the bushing hole 57 for engagement of its end in the recess 58 in the extension 14 of the fin structure which is secured in the opening 13 of the grenade body 10. Now, when the shell is inserted into the bore of a 45 mortar, and the cartridge is fired by a firing pin, the shell will be projected from the mortar. To provide additional projection force, powder or other explosive increments 59 may be inserted in or through slots 60 in the fins 16 so that when 50 the cartridge 55 is fired, the flame therefrom may pass through openings 61 in the fin structure body for firing of the explosive material 59.

Before the shell is put into the mortar, the retention pin 34 is withdrawn. Now, when the 55 shell is projected from the mortar, the latch bolt 44 will be automatically withdrawn to release the safety pin 33 from the latch pin 49 for swing of the safety pin out of its normal position by the spring 43 so that the impact nose 22 will be free to engage its firing cap with the firing pin when the impact nose strikes the ground. This automatic action of the latch bolt is caused by the force of inertia when the shell is projected from the mortar, this inertia effect on the latch 60 bolt causing it to be shifted to withdraw the latch pin 49 from the slot 50 in the safety pin to permit the latch bolt to be moved readily into the bore 45 by the inertia effect, the bolt may be provided with a longitudinal groove 62 for escape of the air out of the bore 45 when the bolt is shifted thereinto.

When the shell is projected from a mortar, the impact nose or cartridge 22 will also be subjected to inertia force tending to shift it inwardly. 75 As the mass of the impact nose is greater than

that of the latch bolt 44, and response of the bolt 44 to the inertia is resisted by the spring 48, the safety pin 33 which normally rests at its outer end on the bottom of the slot 35 and at its inner end on the shoulder 36, will absorb and dissipate the inertia pressure of the impact nose before the inertia becomes effective to shift the latch bolt 44 for unlatching of the safety pin. The impact nose thus remains in its normal or outer position until impact thereof with the ground and then, as the released safety pin has been swung to its released position by the spring 43, the impact nose will be shifted inwardly by the impact for engagement of its firing cap with the firing pin 29, the safety pin, during such inward movement of the impact nose, being swung down as shown on Figure 10. If the shell is to be launched from a rifle, the bushing 54 is withdrawn from the bore of the fin structure and an A. T. grenade launcher 63 is attached to a rifle and its end projected into the fin structure bore 53, as shown on Figure 4. For such rifle launching, powder increments 59 would not be applied to the fins. The powder increment would be applied before launching of the shell from a weapon such as a mortar, but would not be applied for rifle launching or for hand throwing.

In the face of capture by an enemy, the retention pin could be pulled out and the safety pin released from the latch bolt so that the impact nose would be free and any attempt by the enemy to use the shell would probably result in engagement of the impact cartridge with the firing pin and explosion of the shell during launching from a weapon such as a mortar or rifle and with destruction of the enemy within range of the explosion. The shell could also be used as a personal mine or booby trap after withdrawal of the retention pin and release of the safety pin.

I have thus produced a shell which can be thrown by hand or launched by a propelling charge from weapons such as mortars or rifles and which, after impact of the impact nose with the ground, will be hurled back into the air for explosion of the grenade body while in the air by the delayed fuse connection.

I have shown a practical and efficient embodiment of my invention but I do not desire to be limited to the exact construction, arrangement and operation shown and described as changes and modifications may be made without departing from the scope of the invention.

I claim as follows:

1. In a shell of the type described, a grenade body containing explosive material, a nose frame secured to said body, a fuse connection between the interior of said body and said nose frame, an impact member mounted in the end of said frame to project therefrom for axial inward movement upon impact, said impact element containing an explosive and having a firing cap therefor, a firing pin in said frame in the path of said element, a safety bar extending into said frame from the exterior thereof to be normally disposed between said firing cap and pin to prevent engagement thereof, a spring tending to swing said bar laterally out of its normal position, a safety latch normally engaged by the inner end of said safety bar to hold said bar in normal position against the force of said spring, means whereby said bar upon outward manual movement thereof will be released from said safety latch for swing by said spring out of its normal position, whereby, when said shell is thrown and said impact member is

impacted, said firing cap may come into engagement with said firing pin for explosion of said impact member and ignition of said fuse connection and the explosive material in said grenade body.

2. In a shell of the type described a grenade body containing explosive material, a nose frame secured to said body, a fuse connection between the interior of said body and said nose frame, an impact member mounted in the end of said frame to project therefrom for axial inward movement upon impact, said impact element containing an explosive and having a firing cap therefor, a firing pin in said frame in the path of said element, a safety bar extending into said frame from the exterior thereof to be normally disposed between said firing cap and pin to prevent engagement thereof, a spring tending to swing said bar out of its normal position, a safety latch normally engaged by the inner end of said safety bar to hold said bar in normal position against the force of said spring, means whereby said bar upon outward manual movement thereof will be released from said safety latch for swing by said spring out of its normal position, whereby, when said shell is thrown and said impact element is impacted, said firing cap may come into engagement with said firing pin for explosion of said impact element and ignition of said fuse connection and the explosive material in said grenade body, said fuse connection being timed so that the explosion of said impact element may rebound the shell back into the air before the explosive material in said grenade body is ignited.

3. A shell of the type described comprising a grenade body loaded with explosive material and having a fin structure extending from one end thereof, a nose frame secured to the other end of said body and defining a firing chamber, a fuse connection between said firing chamber and the interior of said grenade body, an impact member projecting through the outer end of said nose frame for inward movement therein upon impact on the outer end thereof after projecting of the shell, said impact member containing explosive material and having a firing cap therefor, a firing pin within said firing chamber in the path of said firing cap when said impact element is shifted inwardly, said nose frame having an opening through one side and an internal shoulder on the other side, a safety bar extending through said opening for engaging with its inner end on said shoulder to be normally between said impact element and firing pin and to hold said element in its outer position, a spring tending to swing said safety bar laterally out of its normal position, said bar at its inner end having a bayonet slot, a spring urged latch bolt having a latch pin normally extending into said slot to hold said safety bar on said shoulder and against swing by said spring, a short manual outward movement of said safety bar releasing the inner end of the slot from said latch bolt pin whereby said spring becomes effective to swing said safety bar out of its normal position for exposure of said firing pin to said firing cap when said impact member is shifted inwardly upon impact thereof after projection of the shell.

4. A shell of the type described comprising a grenade body loaded with explosive material and having a fin structure extending from one end thereof, a nose frame secured to the other end of said body and defining a firing chamber, a fuse connection between said firing chamber and the

interior of said grenade body, an impact element projecting through the outer end of said nose frame for inward movement therein upon impact on the outer end thereof after projecting of the shell, said impact element containing explosive material and having a firing cap therefor, a firing pin within said firing chamber in the path of said firing cap when said impact element is shifted inwardly, said nose frame having an opening through one side and an internal shoulder on the other side, a safety bar extending through said opening for engaging with its inner end on said shoulder to be normally between said impact element and firing pin and to hold said element in its outer position, a spring tending to shift said safety bar out of its normal position, said bar at its inner end having a latch slot, a spring urged latch bolt having a latch pin normally extending into said slot to hold said safety bar on said shoulder and against movement by said spring, said latch bolt, upon launching of the shell from a weapon such as a mortar or rifle, being responsive to inertia to withdraw its latch pin from the slot in said safety bar for movement of the safety bar out of normal position by said spring for exposure of said firing pin to said firing cap when said impact element is shifted inwardly upon impact engagement with the terrain or other obstruction.

5. A shell of the type described comprising a grenade body loaded with explosive material and having a fin structure extending from one end thereof, a nose frame secured to the other end of said body and defining a firing chamber, a fuse connection between said firing chamber and the interior of said grenade body, an impact element mounted in the end of said nose frame for inward movement upon impact of its outer end with the ground when the shell is projected, said impact element containing explosive material and having a firing cap, a firing pin in said firing chamber in the path of said firing cap when said impact element is shifted inwardly, said nose frame at one side having an opening and at its other side having an internal shoulder, a safety bar extending through said opening to rest normally with

its inner end on said shoulder so as to be normally disposed below said impact element to hold it in normal position and to be interposed between the firing cap and the firing pin, a spring tending to swing said safety bar away from said shoulder for exposure of the firing pin to the firing cap, said safety bar at its inner end having a latch slot, the base of said nose frame having a bore, a latch bolt movable inwardly in said bore and terminating at its outer end in a latch pin, a spring for said latch bolt normally holding it shifted out with its latch pin in said slot for holding said safety bar in normal position against the force of said first mentioned spring, said latch bolt, upon projection of said shell under a projecting charge, being responsive to inertia to withdraw its pin from said slot whereby said first mentioned spring may swing said safety bar for exposure of said firing pin to said firing cap for explosion of said impact element when it strikes the ground.

6. A grenade firing head having a chamber therein having firing connection with the grenade interior, an explosive impact member within said chamber having a firing cap at its inner end, a firing pin in said chamber in alignment with said firing cap, a safety bar extended through said chamber from the exterior thereof and abutments normally holding said bar against the lower end of said impact member to be interposed between the firing cap and the firing pin, a spring tending to shift said bar from said abutments for exposure of the firing pin to the firing cap, said bar at its inner end having a bayonet slot comprising a transverse portion extending from one edge of the bar and an inner portion extending longitudinally of the bar, a latch pin normally engaging in the inner end of said slot to hold said bar against displacement from its normal position by the spring, a slight outward movement of said bar manually bringing the transverse end of said slot into alignment with said pin whereby said spring may then shift said bar out of its normal position for firing of the impact member upon impact thereof with the ground when the shell is projected.

WILLIAM J. LOWES.
